UNITED STATES PATENT OFFICE.

EMIL SUTHERLAND, OF HOLLYWOOD, CALIFORNIA, ASSIGNOR TO T. W. WOODWORTH, OF LOS ANGELES, CALIFORNIA.

PIPE-WRENCH.

No. 838,665.

Specification of Letters Patent.

Patented Dec. 18, 1906.

Application filed November 9, 1905. Serial No. 286,613.

To all whom it may concern:

Be it known that I, EMIL SUTHERLAND, a citizen of the United States, residing at Hollywood, in the county of Los Angeles and State 5 of California, have invented new and useful Improvements in Pipe-Wrenches, of which the following is a specification.

The object of my invention is to provide a handy, efficient, and simple pipe-wrench 10 which can be easily manipulated with one hand, that will tightly hold the pipe in place therein with sufficient grip to prevent its slipping on the pipe when in use, that is easily adjusted for placement on different- 15 sized pipes and easily removed therefrom. I accomplish these objects by means of the device described herein and shown in the accompanying drawings, in which—

Figure 1 is a side view of my improved 20 wrench in place on a section of pipe, the wrench being in its operative position. Fig. 2 is a view, partly in elevation and partly in section, the handle being broken away, the wrench being in its open inoperative position. 25 Fig. 3 is a plan view of the edge thereof, the handle being in section and partly broken away.

In the drawings, A represents the outer gripping-jaw, integrally attached to the 30 shank B. A handle C is provided with a projecting lug C', by which it is pivotally attached to the opposite end of the shank B, as at D. The inner sliding jaw E has a central opening therethrough for the reception and 35 operation of the shank B. This jaw is provided on its upper end with a socket, in which is pivoted gripping-lug F. This lug is pivoted in the upper end of the sliding jaw, as at G, and has on its outwardly-extending free 40 end serrations H adapted to grip one side of the pipe operated on when the handle of the wrench is thrown upwardly in the act of engaging the pipe, (assuming the wrench to be used on the under side of the pipe, as shown 45 in Fig. 1.) A spiral spring I is placed in a cavity F', formed in the lower part of the pivoted lug and extending outwardly therefrom and rests on the sliding jaw E. This spring will hold the pivoted lug in an upwardly and 50 an outwardly-extending position until the serrations thereon engage the pipe to be operated on, when it will drop down against and rest on the bottom of the recess in the sliding jaw, as shown in Fig. 1, and tightly hold the pipe

operated on between it and the outer jaw A. 55 The sliding jaw E is pivotally connected at its lower end, as at J, with the cross-connecting links K. These links, two in number, are pivotally secured at their other ends to the projecting lugs C' on the handle by the 60 pintle-bolts L. These links, one on each side of the shank B, extend from the pintle-bolt L in the lugs on the handle to the pintle-bolt J in the lower end of the sliding jaw.

Assuming that the wrench is used in the 65 position shown in Fig. 1 and is secured to the pipe from below, the jaws will be caused to grip the pipe M when the handle C is thrown upwardly. The forefinger of the hand operating the wrench will pass around under the 70 shank B about where they are pivoted to the sliding jaw, as at J, the thumb being placed on the projecting lug C' on the handle and pressure applied thereto. This will throw the outer jaw up and cause the sliding jaw to 75 advance toward the outer jaw and close the space between the jaws and grip any object therebetween. Then when the object operated on is gripped between the jaws the elevation of the handle will cause the pipe held 80 between the jaws to turn with the jaws. The moment the handle is dropped the jaws will spread apart and the wrench can be given a new grip on the pipe, or it can be removed, as 85 desired.

The under edge of the shank B is provided with serrations B', adapted to contact with the serrations E'' on the under edge of the opening in the sliding jaw E and prevent the sliding jaw E from movement along the 90 shank B of the wrench, except when the handle is thrown downwardly in opening the jaws of the wrench for taking a new grip or removing the wrench. The wrench being in the position shown in Fig. 2, the handle being down and the jaws being open, when the handle is thrown upwardly into the position shown in Fig. 1 the cross-connecting links K will push the under end of the sliding jaw forwardly, carrying the jaw with it until the serrated lug F on the sliding jaw engages the pipe to be acted on, and the further movement upward of the handle will throw the lower part of the sliding jaw over into contact with the serrations B' on the shank B 100 and prevent any retrograde movement of the sliding jaw and hold the serrations firmly in contact with the pipe. The harder the strain 105

of the handle upward the tighter will be the sliding jaw held in contact with the shank by means of the cross-connecting links.

Having described my invention, what I claim as new, and desire to secure by Letters Patent, is—

1. A pipe-wrench comprising a toothed shank having a fixed jaw on one end, a handle pivotally attached to the opposite end of said shank, said handle having a laterally-projecting lug thereon, a jaw slidably mounted on the shank, and provided with a rigid toothed portion adapted to engage the toothed part of the shank, a connecting-link having one of its ends pivotally attached to one end of the slidable jaw and said connecting-link having its other end similarly attached to the laterally-projecting lug on the handle, whereby lateral pressure upon the handle in one direction causes a tighter grip upon the object to be held or turned.

2. A pipe-wrench comprising a toothed shank having a fixed jaw on one end, a han-

dle pivotally attached to the opposite end of said shank, said handle having a laterally-projecting lug thereon, a jaw slidably mounted on the shank, and provided with a rigid toothed portion adapted to engage the toothed part of the shank, a gripping-lug pivotally connected to the slidable jaw, a connecting-link having one of its ends pivotally attached to one end of the slidable jaw and said connecting-link having its other end similarly attached to the laterally-projecting lug on the handle, whereby lateral pressure upon the handle in one direction causes a tighter grip upon the object to be held or turned.

In witness that I claim the foregoing I have hereunto subscribed my name this 13th day of October, 1905.

EMIL SUTHERLAND.
